UNITED STATES PATENT OFFICE.

ADALINE A. ROCKWELL, OF NEW YORK, N. Y.

DESIGN FOR NECK-TRIMMING.

Specification forming part of Design No. 7,787, dated October 6, 1874; application filed August 11, 1874.
[Term of Patent 3½ years.]

To all whom it may concern:

Be it known that I, ADALINE A. ROCKWELL, of the city, county, and State of New York, have invented a Design for Neck-Trimming, of which the following is a specification:

The nature of my design is fully represented in the accompanying drawing, to which reference is made.

Figure 1 is an outside face or exterior longitudinal view of a piece of neck-trimming made in accordance with my new design. Fig. 2 is a transverse section of the same upon a larger scale. Fig. 3 is a diagram or longitudinal profile on the line $x\ x$ in Fig. 4, which is a longitudinal interior view of the trimming before the same is folded longitudinally.

A is the outside ply, and B the inside ply, of a two-ply trimming, having its longitudinal fold as indicated by the line $x\ x$ in Fig. 4, and being formed with a succession of reversely diagonal transverse flutes or folds, b b, so that when the longitudinal fold is made the outer

ply A resembles a loose fall or curtain over the inside ply B, and each ply presents on its face a succession of truncated points or tapering drops, C, doubled at their edges, as produced by the folds b, and arranged so that the points or drops C on the outer ply A are intermediate of the points or drops C on the inner ply B, thereby conveying the illusion of a zig-zag arrangement of cross folds or bars throughout the length of the trimming, with certain of the bars in front and others behind.

Either or both plys A B may have a lace or bobbinet edge, D; or both may be plain, and a binding, f, applied to the longitudinal fold of the ply.

What I claim as my invention is—

The design for neck-trimmings, substantially as shown in the annexed drawing.

ADALINE A. ROCKWELL.
